BREAKER REEL

Lawrence L. Ludington, Muncie, Ind., assignor to
George A. Ball, Muncie, Ind.

Application January 27, 1937, Serial No. 122,607

8 Claims. (Cl. 19—33)

This invention relates to the art of treating vegetable fibers such as flax, hemp, sisal grass, and the like, and more particularly to improvements in a machine for mechanically breaking the stalks at regularly spaced and relatively short intervals throughout the length of the stalks and for combing or scutching the woody portions or hurds from the fibers.

The principal object of this invention is to provide mechanical means for breaking the woody stalks of fibrous materials without breaking, stretching, straining, or otherwise injuring the fibers carried thereby, and for effectively combing the broken woody portions of the stalks from the fibers whereby prime fibers substantially free from sticking hurds and of substantially the full length of the stalks are produced.

Another object is to provide a mechanical breaker or scutcher in which the breaking and scutching operations are performed by two oppositely rotating reels, each having longitudinally extending and progressively offset breaker bars or beaters with the bars of one reel offset in the opposite direction from the bars on the other reel, whereby the successive offset portions of the bars will be successively brought into co-operating relation with each other on the rotation of the reels to effect the breaking and combing action.

A further object is to provide a pair of breaking and scutching reels which are of different diameters and are driven at different peripheral speeds to effectively comb the broken hurds from the fibers.

A still further object is to provide a breaker or scutcher for removing the woody portions from stalks of fibrous material in which a flow of air is induced through the reels, by the rotation thereof, and directed away from the reels for the purpose of carrying the treated fibers away from the periphery of the revolving reels and prevent the fibers from winding thereon.

A still further object is to provide a breaker or scutcher for removing the woody portions from stalks of fibrous material in which at least one of the reels is provided with means for counteracting the vacuum which has a tendency to form at the back of the beater bars, by directing a current of air along the trailing edges of the bars which supports and carries the fibers away from the periphery of the reels and prevents their winding thereon.

These and other objects which will herein-after be made readily apparent to those skilled in this particular art are accomplished by means

of this invention, one embodiment of which is described in the following specification and illustrated in the accompanying drawings, wherein:

Figure 1 is a plan view of a decorticating machine made in accordance with my invention and showing the position of the beaters or scutchers with respect to the table over which the fibrous material is adapted to be conveyed;

Fig. 2 is a view in elevation of my improved beater or scutcher reels.

Figs. 3 and 3a are sectional views taken on line III—III of Fig. 2;

Fig. 4 is an enlarged sectional view taken on line IV—IV of Fig. 2 and showing the construction of the upper beater reel, and

Fig. 5 is a view in elevation illustrating the mechanism for driving the beater reels.

Referring in particular to Fig. 1 of the drawings, T represents the table of a decorticating machine over which the stalks of fibrous material to be broken and scutched are adapted to be conveyed. The stalks are arranged transversely of the table T and are conveyed there-across (from the right hand to the left hand end of the machine illustrated in Fig. 1) by means of endless conveyor chains C—C¹ which are mounted above the table and which crimp the stalks, intermediate their length, over spaced rails R mounted on the table underneath the chains C—C¹.

The chains C—C¹ which are driven in the same direction from a suitably driven shaft 1 to which they are connected through a series of chain, sprocket, and shaft elements 2, 3, and 4, are arranged in staggered or overlapping relation so that the stalks will be first engaged and conveyed a portion of the length of the table T by the chain C and will then be transferred, at a point intermediate the ends of the table, to the chain C¹ which conveys the fibers the remaining length of the table T. As the stalks are conveyed lengthwise of the table, the ends thereof project a progressively greater distance beyond diagonal edges 5—5a on opposite sides of the table T and extend between oppositely rotating reels or breakers B—B¹, which are positioned adjacent the diagonal edges 5—5a, respectively, and which break the stalks over the table edges 5—5a and scutch the hurds or broken woody portions from the fibers.

The diagonal edges 5—5a are so formed on the table T that the rear end of the edge 5 is substantially opposite the front end of the diagonal edge 5a and as a result of this construc-

tion and of the overlapping of the chains C—C1, it is apparent that the treated fibers leaving the breaker B will be engaged by the chain C1 and the portion formerly engaged by the chain C 5 will pass through the breaker B1 whereby all portions of the stalks will be acted upon by the breakers B—B1.

Each of the breakers B—B1 (Fig. 2) are of similar construction and comprise a small upper reel 20 and a large lower reel 30 which are continuously rotated in opposite directions to break the woody portions of the stalks projecting between the reels and scutch the broken hurds from the fibers.

15 The top reel 20, which is of smaller diameter than the bottom reel 30, comprises a cylindrical member 21 keyed at each end on a shaft 22 which is journaled at each end in a member 23 which forms the housing for the breaker B—B1. The 20 cylinder 21 carries four radially projecting and circumferentially spaced composite beater bars, each of which is formed of a series of relatively short web-like members 24a which are longitudinally and successively offset in the same direction and have their contiguous ends joined together by suitable web-like members 24b. Thus, the members 24a—24b form a composite beater bar which extends lengthwise of the cylinder 21 and is offset at intervals in the same direction 25 to provide a series of steps in said bar.

30 The ends of the cylindrical members 21 are provided with a series of openings 25 and the body of the cylinder is provided with openings 26 adjacent the rear face of each of the elements 35 24a, the purpose of which will be hereinafter more fully described.

The lower reel 30 comprises a central shaft 31 which is journaled in the housing 23 below and slightly in front of the shaft 22 which carries the 40 upper reel 20. The shaft 31 has a series of members 32 at spaced intervals along the length thereof each of which is provided with a series of ten radially projecting and spaced arms 33. Each succeeding member 32 is turned slightly 45 on the shaft 31 so that the front face of each of the arms 33 on each succeeding member is substantially aligned with the rear face of the arms 33 on the next preceding member 32. The arms 33 on the succeeding members 32 are joined 50 together by bars 34; one end of each bar 34 is attached to the rear face of an arm 33 on one member 32 and to the front face of an arm 33 of the next succeeding member 32 whereby a series of ten circumferentially spaced breaker bars are provided which extend lengthwise of the reel 30 and are regularly and successively offset 55 in the same general direction. The bars 34 on the reel 30 are offset in the opposite direction from the offsets in the bars on the reel 20 and as a result, as the reels are rotated in opposite directions, successive bars 24a on the reel 20 come 60 into cooperating relation with successive bars 34 on the reel 30.

The shafts 22 and 31 are so arranged and 65 spaced vertically, that as the reels 20 and 30 rotate in opposite directions, the bars 24a will project between and overlap with the bars 34 on the reel 30 and in order to permit the reels to rotate freely without interference between the 70 beater bars on the two reels, the members 24a are of such length and are so positioned that the webs 24b pass by the outer faces of arms 33.

The breakers B—B1 are preferably so positioned adjacent the diagonal edges 5—5a of the 75 table T that the bars 24a of the upper reels 20

first come into contact with the ends of the fibers projecting beyond such edges and break the stalks downwardly over that edge of the table. The broken ends of the stalks are then picked up by the bars 34 on the lower reels 30 which are rotating in the opposite direction from the reels 20 and since the bars on the reels overlap a combing action is produced which strips the hurds from the fibers, as they move lengthwise through the breakers B—B1.

10 Since the upper reel 20 is provided with only four circumferentially spaced breaker bars 24a while the lower reel 30 has ten such breaker bars 34, it is apparent that the upper reel must be driven 2½ times as fast as the lower reel 30 15 in order that one of the bars 24a will project between each of the bars 34 on the arms 30 and to secure this timing, the shafts 22 and 31 of the reels 20 and 30 of each of the breakers B—B1 are connected by a series of gears 36 having the 20 required ratio and the gears 36 are driven from a continuously driven shaft 37, one end of which is geared directly to the gears 36 connecting the shafts 22—31 of the breaker B (Fig. 1). The gears 36 connecting the shafts 22—31 of the breaker B1 are driven from the shaft 37 through the belt and pulley elements 38—39 and the shaft 40 which is geared to the gears 36 of the breaker B1.

30 Decorticating machines have been made heretofore in which oppositely rotating reels were employed to break and scutch the woody portions of the stalks from the fibers. However, these machines have not been entirely satisfactory, due, primarily to the fact that the fibers 35 had a tendency to wind on the periphery of the reels. I believe that the difficulty encountered in these machines, all of which have reels of open construction, results from the creation of a partial vacuum along the trailing edges of the rapidly rotating beater bars which tends to pull the fibers into the reel and cause them to wind thereon. However, with breakers constructed in accordance with my invention, such winding of the fibers on the reels is prevented since a current of air is induced to flow through the openings 25 into the interior of the cylinder 21 on the rotation of the reels 20 which is discharged through the openings 26 at the rear or trailing faces of the solid bars 24a and not only counteracts the vacuum at that point but also carries the fibers away from the periphery of the reels 20 and 30 since the air discharged through the openings 26 along the trailing faces of these bars is directed or passes outwardly from the 50 reel in front of the next succeeding bar (Fig. 4) supporting and carrying the fibers away from the rotating members and preventing the winding thereon.

55 From the foregoing description it is apparent that an apparatus made in accordance with my invention will effectively remove substantially all the woody matter from the fibers without breaking, weakening, or otherwise injuring the fiber to any appreciable extent and that as a result, prime fibers of substantially the full length of the stalks will be produced.

Further, as a result of the induction of a current of air through the reels and directing it away from the reels the treated fibers will be 70 supported and carried away from the periphery of the reels and winding thereon is prevented.

75 While I have described one embodiment of my invention, it is apparent that certain other modifications, changes, omissions, and substitutions

may be made therein without departing from the spirit of my invention and the scope of the appended claims.

What I claim as new and desire to secure by

5 Letters Patent is:

1. Apparatus of the character described comprising a shaft, a series of spaced spiders on said shaft, and bars connecting the outer ends of the arms on adjacent spiders, one end of each of said 10 bars being secured to the front face of an arm on one spider and to the rear face of an arm on the adjacent spider to provide a longitudinally extending beater having regularly recurrent offsets therein.
- 15 2. A beater reel comprising a central shaft, a series of spiders having radially projecting arms secured to said shaft at regularly spaced intervals, each succeeding spider being so mounted on said shaft that the front faces of the arms thereon 20 are substantially aligned with the trailing faces of the arms on the preceding spider, and bars connected to the outer ends of the arms of adjacent spiders.
- 25 3. A beater reel comprising a central shaft, a series of spiders having radially projecting arms secured to said shaft at regularly spaced intervals, each succeeding spider being mounted on said shaft so that front faces of the arms thereon are substantially aligned with the trailing faces of 30 the arms on the preceding spider, and beater bars between the arms of adjacent spiders, each bar having one end secured to the front face of the arm on one spider and to the trailing face of the arm on the adjacent spider.
- 35 4. A beater reel comprising a shaft, a series of members carried by said shaft each having a plurality of radially extending arms thereon, each of said members being so positioned on the shaft that the front faces of the arms thereon are substantially aligned with the trailing faces of the 40 arms on the preceding member, and bars secured to the opposite faces of the arms on adjacent members.
5. Apparatus of the character described comprising a pair of oppositely rotating reels of different diameters, each reel having longitudinally extending offset beater bars thereon, the bars on said reels being offset in opposite directions, means for feeding fibrous material progressively between said reels, and means associated with one of said reels for holding the treated ends of said material away from said reels to prevent winding thereon.
- 10 6. Apparatus of the character described, comprising a pair of oppositely rotating reels of different diameters, each of said reels having a series of beater bars extending lengthwise thereof and offset longitudinally to provide successive steps in each of said bars, the step on said reels extending in opposite directions, means for rotating said reels, and means for feeding fibrous material progressively between said bars.
- 15 7. Apparatus of the character described, comprising a pair of oppositely rotating reels of 20 different diameters, each of said reels having a series of beater bars extending lengthwise thereof and offset longitudinally to provide successive steps in each of said bars, the step on said reels extending in opposite directions, means for rotating said reels, means for feeding fibrous material progressively between said bars, and means for pneumatically supporting the treated ends of said 25 fibrous material.
- 30 8. Apparatus for treating fibrous material, comprising a pair of oppositely rotating reels of different diameters, each of which is provided with a series of circumferentially spaced beater bars extending lengthwise thereof and offset longitudinally to provide successive steps therein, 35 the steps on said reels extending in opposite directions, means for rotating said reels, means for feeding fibrous material progressively between said reels, and means associated with the reel of smaller diameter for discharging air along the 40 trailing edges of the bars carried thereby to carry the treated fibers away from said reels.

LAWRENCE L. LUDINGTON.
